COMBINED GOLF TEE INDICATOR, BALL WASHER, WASTE RECEPTACLE AND SHOE SCRAPER

Leslie Leonard Sapier, Vaucluse, New South Wales, Australia, assignor to Maria Sapier, Vaucluse, New South Wales, Australia

Filed Apr. 12, 1973, Ser. No. 350,478

Term of patent 14 years

Int. Cl. D21—02
U.S. Cl. D34—5 CB

FIG. 2.

FIG. 1 is a front perspective view of a combined golf tee indicator, ball washer, waste receptacle and shoe scraper showing my new design; and

FIG. 2 is a rear perspective thereof.

I claim:

The ornamental design for a combined golf tee indicator, ball washer, waste receptacle and shoe scraper, substantially as shown.
